UNITED STATES PATENT OFFICE

2,098,690

CONTAINER

Alfred R. Metzger, White Bear Lake, Minn.

Application February 15, 1934, Serial No. 711,438

8 Claims. (Cl. 229—47)

My invention relates to an improvement in containers, and more particularly the type of containers readily adaptable for containing butter, lard, or any dry or semi-liquid substance for shipping purposes.

It is the purpose of my invention to provide a waterproof and greaseproof container which is so constructed to withstand a great amount of strain without damage. My construction is particularly adaptable to use on laminated tubs of paper or other material, and it is my object to make the laminations greater in number at points where the container is subjected to greatest strain.

It is the purpose of my invention to provide a means of reinforcing the cover of the container, so that it will hold its proper shape and resist transverse strain as would occur when a container was being squeezed transversely between two objects. By this means I have been able to provide a laminated paper tub which will withstand more strain by several times than a wooden container of similar size and of greater weight.

It is an object of my invention to provide a means for holding the cover of the container in place, and of sealing the cover against tampering with the contents of the container. By this means, I am able to further reinforce the container top against various types of strain to which the container might be subjected. My cover-holding means, despite these advantages and important features, is readily openable when desired, and may be closed quickly and easily.

It is a feature of the preferred form of my construction that the cover-securing means acts to reinforce the top or cover of the container against downward strain imposed by an article or another container placed on the top cover of the container. This is accomplished by providing a pair of crossed metal bands which secure the cover in position, and which transmit compression strain across the top and to the edge of the cover where the strain may be borne by the side walls of the container.

It is a feature of my invention that the cover-securing means may be entirely removed from the body of the tub when it is desired in order that the tub may be reconditioned. The removability of the securing means also permits this means to be readily replaced, as the securing means is more easily worn out than is the body of the tub, and may need replacement before the container is worn out.

These and other objects of my invention will be more fully and clearly set forth in the following specification:

In the drawings forming a part of my specification:

Figure 1 is a perspective view of a container of my construction with the cover and securing means therefor in position.

Figure 2 is a cross-sectional view centrally through the tub.

Figure 3 is a cross-sectional view of a detail portion of the container, illustrating the manner of securing the cover in place.

Figure 4 is a cross-sectional view of a portion of the reinforcing means used for the edge of the cover of my container.

Figure 5 is a bottom plan view of a cover for my container, illustrating the securing means enclosed therein in the position employed for shipping the covers and securing means.

Figure 6 is a sectional detail of a portion of the cover and side wall of a container of slightly modified form.

Figure 7 is a bottom plan view of the cover of the container shown in Figure 6, in the position assumed for shipping the covers.

Figure 8 is a perspective view of a detail portion of the container reinforcing band used in the modification illustrated in Figure 6.

Figure 9 is a perspective view of a detail portion of my securing means.

Figure 10 discloses the band of Figure 8, used in conjunction with cover straps as shown in Figures 1, 2 and 3.

As best illustrated in Figure 2 of the drawings, my container A is formed with side walls 10 formed of a number of laminations of paper 11 or other suitable material. The side walls preferably taper, as illustrated, for nesting purposes. Between each lamination of paper is a coating 12 of waterproof or greaseproof glue, providing a plurality of waterproof surfaces through which no moisture or grease can penetrate.

A bottom of laminated paper 13, is likewise provided with a waterproof and greaseproof glue 12 between each lamination 14. The bottom 13 is formed with a flat portion 15 and with integral side walls 16 which are pressed against the bottom of the side walls 10 and held in this position by reinforcing rings 17 of laminated paper. The rings and bottom are preferably glued in place, and held firmly in position by means of metal staples 18.

The side walls 10 are so rolled that the lower portion thereof are slightly thicker, due to a greater overlap of the laminations, which are formed of a number of separate sheets secured together. In this manner, the lower portion of

the container is capable of withstanding a great amount of strain.

The cover 19 of the container A is formed in a manner similar to the bottom 13 of a series of 5 sheets 20 held together by means of water proof and greaseproof glue, and is substantially flat with a downturned flanged edge 22 about the perimeter thereof. This flanged edge 22 is reinforced by means of a metal hoop 23 of the type 10 indicated in Figure 4. The hoop 23 is bent slightly inwardly at its upper edge 24, and is bent or crimped over the flanged edge as shown in Figures 2 and 3 to entirely enclose this edge.

In preferred form, the cover 19 is held in place 15 upon the container by a harness B illustrated in Figures 1, 2 and 3. The harness B comprises a hoop 25 of just sufficient diameter to slip up over the tub from the bottom thereof to a position spaced somewhat from the top edge 26 of the 20 container side wall 10. This hoop 25 is provided with two pairs of oppositely disposed offset portions 27 which accommodate straps 28 and 29 to encircle the hoop at these points while it is in position on the container.

25 One end of each strap 28 and 29 encircles the hoop 25 in one of the offset portions, and is held by the clip 30 securely to the hoop at all times. The clip 30 merely encircles the looped ends of the strips, and is crimped in such a manner to hold the strip in this position. The extreme end 32 of each of the strips 28 and 29 is bent down over the clip 30, as shown in Figure 2.

The other end 33 of each of the strips 28 and 29 is secured to the hoop 25 at a point diametrically opposite the permanently fixed end by looping this end 33 under the hoop 25 at the diametrically opposite offset portion 27, looping this end 33 around the hoop 25, and inserting this end through a slid able clip 34 on the strip 28 or 29. 40 The clip 34 merely encircles the strip 28 or 29 and the end 33. When the end 33 has been inserted through the clip 34, this clip may be slid down adjacent the hoop 25. For additional security, the end 33 of the strip 28 or 29 may be 45 bent down over the clip 24 to prevent this clip from sliding upwardly, although there is little danger of this. The formation of the clip 34 may be seen in Figure 9 of the drawings.

In order to enable the shipper to secure the 50 cover tightly in place, a hole 35 is formed in the end 33 of each of the strips 28 and 29. A tool such as a common nail may be inserted through this hole to enable the shipper to better grasp the strip for drawing it tight.

55 The hole 35 may also serve the purpose of permitting a seal 36 to be looped through the offset 27 of the hoop 25 and through the hole 35 when the clip 34 is engaging the end 33 of the strip 28 or 29. The top or cover 19 then cannot be removed until this seal is broken or the wire securing the seal is cut. In this manner the cover 60 may be sealed against tampering, and the shipment would not be received if a seal was broken.

65 For shipping purposes, the hoop 25 and the straps 28 and 29 are enclosed within the cover 19 in the manner illustrated in Figure 5 of the drawings. The covers, containing the harness B, can be packaged separately from the side wall and bottom portions of the container, which are nested together in shipping.

70 If it is desired, I may make the cover 19 in the manner illustrated in Figure 6, in which the cover is further reinforced by means of an inner hoop 37 to which are secured attaching strips 38 at intervals about the periphery thereof. This inner

hoop 37 is placed within the flanged edge 22 of the cover 19, and is held in position by the hoop 23, which is crimped up over the inner hoop 37 as well as over the edge 22.

A flat band 41 encircles the container A in the 5 approximate position occupied in the preferred structure by the hoop 25, and is provided with offset portions 39 forming lips through which the ends of the attaching strips 38 may pass. The free ends 40 to these attaching strips 38 are then 10 bent upwardly and inserted under the flanged edge 22 of the cover 19 as illustrated in Figure 6 of the drawings. The formation of the offset portions 39 may be seen in Figure 8.

15 It is obvious that, if desired, the two forms 15 illustrated may be combined, and the flat band 41 may be used in combination with the crossed strips 28 and 29. Similarly, the hoop 25 could be used with the modification of cover illustrated in Figure 6, being used in place of the flat band 41. 20

25 In shipping, the modification of cover illustrated in Figure 6 would appear as illustrated in Figure 7 of the drawings. The flat attaching strips 38 are bent down parallel with the flat portion of the cover 19, and the covers are bundled 25 one against the other.

If found desirable for certain purposes the hoop 25 or the flat band 41 could be attached to the side walls of the container. In Figure 8 I illustrate the band 41 being indented at points 42 30 about the periphery of the same, forcing these indentations into the side walls 10 and thus preventing relative movement of the band and the side wall 10. The entire container including the side walls 10, bottom 13 and cover 19 is dipped 35 into a paraffin solution or other surfacing material which coats the outside surface of the material and also is absorbed into the paper and into any cracks between various laminations or adjoining parts. This coating effectively preserves 40 the surface of the containers. In reconditioning the containers, it is possible to steam the same to remove the surface paraffin, and recoat the tubs.

In accordance with the patent statutes, I have described the principles of my invention, and 45 while I have endeavored to set forth the best embodiment thereof, I desire to have it understood that this is only illustrative of a means of carrying out my invention, and that obvious changes 50 may be made within the scope of the following 50 claims without departing from the spirit of my invention.

I claim:

1. A securing means for the cover of a container comprising, a flat hoop encircling the 55 container at a point spaced from the top thereof, diametrically opposed offset portions on said hoop extending a fraction of the width of said hoop, and flat strap means extending from one offset portion on said hoop over the top and 60 cover of said container, and secured to another offset portion at a point diametrically opposite said first-mentioned point.

2. In combination, a container comprising tapered side walls, a bottom within said side walls, a 65 container cover, a flat hoop about said side walls spaced from the large end of the container, diametrically opposed offset portions on said hoop and flat strap means connecting said diametrically opposite offset portions on said hoop 70 to hold the container cover on the large end of the container.

3. In combination, a container having tapered side walls, a bottom secured to said side walls, a band spaced from the top larger end of said 75

5 side walls having diametrically opposed openings therethrough, a cover for said container on the larger end of said container, and flat strap means over said cover and secured to said band through said openings at diametrically opposite points thereupon.

4. In combination, a container having tapered side walls, a band about said side walls at a point spaced from the top thereof, a cover for 10 said container, a flanged edge about said cover, an inner reinforcing band within said flanged edge, an outer reinforcing edge crimped over said inner band to hold the inner band in place, and attaching strips secured to said inner band engageable with said band about said side walls 15 to hold the cover in place.

5. In combination, a container having tapered side walls, a band about said side walls, offset portions on said band extending a fractional portion 20 of the width of said band, a cover for said container to fit over the large end thereof, flat band means for securing said cover to said container adapted to be looped through said offset portions of said hoop.

6. In combination, a container having tapered walls, a band about said walls at a point spaced from the top thereof, a cover for said container, a flanged edge about said cover, an outer reinforcing band on said flange crimped over a portion 5 of the inside of said flange, anchoring strips adapted to engage said first-named band, and means for anchoring said strips within said crimped portion of said reinforcing band.

7. A container cover including a top portion, 10 a flanged edge about said top portion, an outer reinforcing band on said flange crimped over a portion of the inside of said flange, anchoring strips, and means for anchoring said strips within 15 said crimped portion of said reinforcing band.

8. A container including in combination, container walls, a band about said walls at a point spaced from the top thereof, offset portions in 20 said band, a fraction of the width of said band providing loops, a container cover and means attached to said cover adapted to extend through said loops to seal said cover to said container.

ALFRED R. METZGER.
